CLAIM

The ornamental design for a liquid crystal display clock, as shown and described.

DESCRIPTION

FIG. 1 is a front perspective view of a liquid crystal display clock showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings are used to show portions of the liquid crystal display clock that do not form part of the claimed design.
